UNITED STATES PATENT OFFICE.

AUGIE L. HANSEN, OF CHICAGO, ILLINOIS, ASSIGNOR TO A. L. HANSEN MFG. COMPANY, OF CHICAGO, ILLINOIS, A CORPORATION OF ILLINOIS.

SLIDING-DOOR FIXTURE.

Application filed June 10, 1925. Serial No. 36,076.

This invention relates to improvements in sliding door fixtures, and more particularly to fixtures for supporting the sliding door of vehicle cabs or enclosures.

The object of the invention is to provide a practical, inexpensive and wholly dependable roller or hanger equipment for sliding doors and characterized by such features as simplicity of construction, ease of attachment, with complete elimination of rattling or displacement of the door under the ordinary conditions of vehicle operation.

A preferred embodiment of the invention is disclosed in the accompanying drawings, in which

Figure 1 is a view in side elevation of an ordinary vehicle cab having a sliding door equipped with the improved fixtures;

Figure 2 is a perspective view of a door hanger such as would be applied at the top of the sliding door;

Figure 3 is a hanger adapted to be attached at the bottom of the sliding door;

Figure 4 is a perspective view of a retaining roller which cooperates with either the top or bottom hangers shown in Figures 2 and 3;

Figure 5 is an enlarged detail view in vertical section taken on line 5—5 of Figure 1, and showing a typical hanger installation where the door is hung from its top edge by means of hangers such as disclosed in Figure 2;

Figure 6 is an enlarged view in elevation of the lower section of a sliding door showing the hangers mounted at the lower edge of the door; and

Figure 7 is an enlarged detail view in vertical section similar to Figure 5, showing the door supported at its lower edge by hangers of the type shown in Figure 3.

Figure 1 represents a typical cab or enclosure 1, for the driver's compartment of a commercial motor vehicle, constructed in accordance with the standard practice of body makers. On each side of the cab is a doorway provided with the usual type of panelled sliding door 2, mounted exterior of the cab and sliding backwardly and forwardly to open and close the doorway. Along the front edge of the door is provided a lock 3 of any suitable type. Figures 5 and 6 disclose the essential details of the cab in which the roof is represented by the

member 4, and the doorway by a transverse frame member 5, extending across the top of the doorway and vertical side frame members 6 extending down to the floor 7.

The cab door 2, being relatively light in weight, may be either suspended from hangers applied to the top edge of the door and riding on a track extending along the top of the doorway, or it may be supported by hangers attached to the bottom edge of the door and engaging a track extending along the cab at the floor level. Either method of hanging the door may be employed, the choice being ordinarily left to the body manufacturer, although either method is equally satisfactory. For this reason both methods have been illustrated and described. Thus, Figure 1 and Figure 5 disclose the method of suspending the door from hangers along its top edge and Figure 6 shows the use of the hangers along the lower edge.

Referring now to the disclosures of Figures 1, 2 and 5, the door supporting member consists of a track-plate 8, extending horizontally above the doorway and screwed or otherwise attached flatwise to the exterior of the cab. The lower edge of the track plate is bent to form a U-shaped flange 8^a turning outwardly and upwardly, the edge of this flange forming a track spaced a short distance from the main portion of the track plate. Fastened to the upper edge of the door 2, are hangers 9, preferably two in number and located near the front and rear ends of the door, as shown in Figure 1. A hanger 9, of the kind shown in Figure 2, comprises a frame member of sheet metal shaped to form a base web 9^a and an inverted U-shaped roller support 9^b offset laterally from the plane of the base web by a short intermediate transverse web 9^c. A hard steel roller 11 is mounted within the roller support 9^b and has short axles 11^a, which engage two corresponding bearing slots 10, formed in the two vertical webs of the roller support, and extending horizontally thereof. Thus the roller is free to roll lengthwise of the hanger and to rotate on its axles.

As clearly shown in Figure 5, the hangers are applied to the door 2, with the base web 9^a flatwise against the outer face of the door with its upper edge fitting in a shoulder formed by the short transverse web

9°, with roller support 9^b offset inwardly and located centrally above the top edge of the door. The hanger, thus being attached, preferably by bolts 12 which pass through the door-frame and bolt holes 13 in the base flange 9^a of the hanger, is hung on a track 8 with the upturned track flange 8^a engaging the rollers 11 and the inner or free web of the roller support 9^b extending between the track-plate and the upturned track flange 8^a. Extending along the track plate is a sheet metal housing or hood 14, which serves to protect the track and hangers against weather conditions and also to conceal the fixture.

As clearly shown in Figure 5, the lower edge of the door extends a short distance below the floor 7, and to the bottom edge of said door are attached a pair of retaining rollers 15^c, there being preferably two of these retaining rollers used in an ordinary installation and preferably arranged as shown in Figure 1. Figure 4 shows the complete assembly of one of these retaining rollers, which comprises a strip 15^a, of resilient metal such as spring steel, having mounted at one end a journal block 15^b, at one end of which a grooved disk or roller 15^c is journaled. As clearly shown in Figure 1, the strips are fastened end to end near the center of the door-frame and extend lengthwise thereof in opposite directions so that the rollers 15^c are disposed just inwardly from each end of the door. Moreover, as clearly shown in Figure 5, the rollers 15^c are offset inwardly from the door and clear the lower edge thereof by a distance of a quarter of an inch or so.

Fastened along the edge of the floor 7 is a longitudinal plate or strip 16 having its top and bottom edges extending a short distance above and below the floor 7. The lower edge of the plate 16 forms a downwardly facing track along which ride the retaining rollers 15^c. Along the lower edge of the door-frame is preferably attached a plate 17 with its lower portion projecting downwardly below the retaining rollers and thus serving to conceal them from view and to protect them from injury.

It is manifest that, in order to place the retaining rollers 15^c into rolling contact with the lower edge of the plate 16, it is necessary to spring the strips 15^a in a downward direction, thus placing them under tension, which acts in a vertical direction to hold the rollers 11 more firmly on their track, and thus prevent rattling, as well as any tendency for the rollers to jump the track in case of an unusually violent shock or jar, as for instance when the vehicle is moving over a particularly rough pavement.

As already explained, the top hangers 9 may be eliminated entirely and bottom hangers, such as shown in Figure 3, sub-

stituted for them. Figure 6 shows an installation in which the bottom hangers are used. In this case, the upper edge of the door slides in a simple form of rabbet 18, extending along the top of the door-frame 70 in place of the track plate 8 and the housing 14.

The construction at the lower edge of the door is identically the same as already described, namely, with the plate 16 extending 75 along the edge of the floor and the retaining rollers 15^c attached to the underside of the door-frame and engaging the lower track plate 16 in the same manner as shown in Figure 1.

The bottom hangers 19 are applied to the bottom edge of the door-frame and against the inner face thereof, each being located near the front and rear end of the door in substantially the same corresponding positions as were the top hangers in the previously described arrangement. The bottom door hangers are somewhat different in design from the top hangers, as clearly revealed in comparing Figures 2 and 3, 85 90 although in general construction and design they are essentially the same. Thus a bottom door hanger is constructed of sheet metal shaped to form a main vertical web 19^a, having its upper portion bent at right angles and thence downwardly to form a parallel web 19^b terminating substantially midway between the upper and lower edges of the main vertical web 19^a and forming therewith the downwardly opening U-shaped 95 100 roller support having the same arrangement of lengthwise extending parallel slots 20 and supporting a grooved roller 21, having axles 21^a which ride in the slots 20, as before.

Along the lower edge of the main web 19^a is a short transverse flange 19^c, formed by bending the lower edge portion of said web at right angles in the same direction as the upper portion is bent to form the inverted U-shaped roller support.

As clearly shown in Figure 6, each bottom hanger 19 is screwed or otherwise fastened to the inner face of the door and near its lower edge, and in such a way that the lower flange 19^c projects inwardly just below the lower edge of the door and in such position just clears the under side of the floor track plate 16. Similarly, the U-shaped roller support at the upper end of the hanger extends above the track plate 16 with the roller 21 engaging the top edge thereof.

In this arrangement the door is supported on the lower track plate but otherwise it slides in the same manner as heretofore described in connection with the top hanger. Likewise the retaining rollers 15^c co-operate with the bottom hangers in the same way to prevent rattling or displacement of the door. It is to be noted also that the lower flanges 19^c prevent the hangers from being displaced 120 125 130.

from the track plate 16 by positively limiting the vertical displacement of the door with respect to the track.

Having set forth the preferred embodiment of the invention and the structural and operative advantages thereof, I claim as my invention:

1. The combination of a sliding door and a horizontal track extending adjacent one edge of said door, a hanger attached to the door adjacent said track and comprising an inverted U-shaped roller support positioned above the track, and a roller journaled in said support and engaging the top edge of said track, and a retaining roller mounted at the lower edge of the door and adapted for yielding rolling contact with a downwardly facing surface adjacent said lower edge of the door.
2. The combination with a sliding door of a supporting track, a hanger comprising a roller engaging said track, a track plate extending horizontally adjacent the lower

edge of said door, a resilient arm fixed at one end to the lower edge of said door, and a roller journaled at the free end of said arm and engaging the lower edge of said track plate.

3. The combination of a sliding door, a vertically disposed track plate extending horizontally adjacent one edge of said door, hangers attached to said door and comprising rollers engaging the upper edge of said track plate, a track plate extending horizontally adjacent the lower end of said track plate, and retaining rollers attached to the lower edge of said door and comprising resilient arms extending in opposite directions in the plane of the door and having at the ends of said arms rollers offset from the plane of the door to engage the lower edge of said lower track plate.

Signed at Chicago, Ill., this 5 day of June, 1925.

AUGIE L. HANSEN.
